ATTORNEYS

UNITED STATES PATENT OFFICE.

DAVID B. BAUDER, OF MENOMINEE, MICHIGAN.

WINDOW-SCREEN.

SPECIFICATION forming part of Letters Patent No. 236,754, dated January 18, 1881.

Application filed April 6, 1880. (Model.)

To all whom it may concern:

Be it known that I, DAVID B. BAUDER, of Menominee, in the county of Menominee and State of Michigan, have invented certain new and useful Improvements in Window-Screens; and I do hereby declare that the following is a full, clear, and exact description of the invention, which will enable others skilled in the art to which it appertains to make and use the same, reference being had to the accompanying drawings, which form a part of this specification, and in which—

Figure 1 is a view of a window-frame with sashes to which my improvement has been applied. Fig. 2 is a vertical sectional view of one of the sashes. Fig. 3 is a cross-section of the same. Fig. 4 is a side view of the same, and Fig. 5 is a perspective view of the fastening-plate of the friction-strip detached.

Corresponding parts in the several figures are denoted by like letters of reference.

This invention relates to that class of window sashes or screens which are held in position by the friction against the window-frame of a strip pressed outward by means of suitably-arranged springs; and it consists, essentially, in the construction of an improved fastener for securing such friction-strip in position, as will be hereinafter more fully shown and described.

In the drawings, A represents the window-frame, which is provided on one side with a groove, B, to fit a strip, C, upon one side of the sash D. Upon its other side the frame D is provided with a groove, E, to receive the friction-strip F, which is fitted in a groove in the adjoining side of the sash. Suitable springs, H H, are placed in groove E, to force the strip F outward and create sufficient friction to retain the sash at any desired elevation.

To secure the friction-strip F in position I employ metallic plates I, arranged in groove E, adjoining the said strip, and having its outer end bent, as at J, to fit over the edge of the sash, and provided with a perforation, K, 45 to receive the screw by which the plate is secured to the sash. The body of plate I is provided with a slot, L, to receive the head of a screw or pin, M, which is permanently secured in the side of strip F, contiguous to the plate. 50

The operation will be seen at a glance. The plate I J, while preventing the strip F from being displaced, permits it to work freely in the direction of the tension of the springs H and perform the function assigned for it. 55

One or more of the fastening-plates may be employed to hold each strip F in position, and when two or more are used they may be arranged on opposite sides and at opposite ends of the strip. 60

Having thus described my invention, I claim and desire to secure by Letters Patent of the United States—

The combination, with the grooved or recessed sash D, of the spring friction-strip F 65 and slotted plates I J, having their outer bent part, J, permanently secured upon the sash, and their slotted part I extending into its groove or recess and engaging with a screw or headed pin, M, secured permanently on the 70 contiguous side of strip F, substantially as and for the purpose herein shown and specified.

In testimony that I claim the foregoing as my own I have hereto affixed my signature in 75 presence of two witnesses.

DAVID BENONA BAUDER.

Witnesses:

AUGUSTUS SPIES,
BENJAMIN T. PHILLIPS.
